CLAIM

The ornamental design for a ring sizer, as shown and described.

DESCRIPTION

FIG. 1 is a top perspective view of a ring sizer showing our new design.

FIG. 2 is a bottom perspective view thereof.

FIG. 3 is a left side view thereof.

FIG. 4 is a right side view thereof.

FIG. 5 is a top view thereof.

FIG. 6 is a bottom view thereof.

FIG. 7 is a front view thereof.

FIG. 8 is a rear view thereof.

FIG. 9 is a top perspective view of another ring sizer showing our new design.

FIG. 10 is a bottom perspective view thereof.

FIG. 11 is a left side view thereof.

FIG. 12 is a right side view thereof.

FIG. 13 is a top view thereof.

FIG. 14 is a bottom view thereof.

FIG. 15 is a front view thereof.

FIG. 16 is a rear view thereof.

FIG. 17 is a top perspective view of still another ring sizer showing our new design.

FIG. 18 is a bottom perspective view thereof.

FIG. 19 is a left side view thereof.

FIG. 20 is a right side view thereof.

FIG. 21 is a top view thereof.

FIG. 22 is a bottom view thereof.

FIG. 23 is a front view thereof; and,

FIG. 24 is a rear view thereof.
